AIRPLANE

Armand J. Thieblot, Hagerstown, Md.

Application August 11, 1953, Serial No. 26,406

Term of patent 14 years

(Cl. D71—1)

Fig. 1

The other side, not shown, is like the side shown.

The essential features of my design reside in the portions shown in full lines.

I claim:

The ornamental design for an airplane, as shown and described.
